US00D726502S

(12) **United States Design Patent** (10) **Patent No.:** **US D726,502 S**
Broen et al. (45) **Date of Patent:** **** Apr. 14, 2015**

(54) **CUP**

(71) Applicant: **PepsiCo, Inc.**, Purchase, NY (US)

(72) Inventors: **Martin Eduardo Broen**, New York, NY (US); **Christopher Erlin Granneberg**, Brooklyn, NY (US)

(73) Assignee: **PepsiCo, Inc.**, Purchase, NY (US)

(**) Term: **14 Years**

(21) Appl. No.: **29/473,519**

(22) Filed: **Nov. 22, 2013**

(51) LOC (10) Cl. **07-01**

(52) U.S. Cl. USPC **D7/529**; D7/509; D7/535; D7/523; D7/532; D7/537

(74) Attorney, Agent, or Firm — Banner & Witcoff, Ltd.

(57) **CLAIM**

The ornamental design for a cup, as shown and described.

DESCRIPTION

FIG. 1 is a top, front perspective view of a cup showing our new design;

FIG. 2 is a front view thereof;

FIG. 3 is a right side view thereof;

FIG. 4 is a rear view thereof;

FIG. 5 is a left side view thereof;

FIG. 6 is a top view thereof; and,

FIG. 7 is a bottom view thereof.
